UNITED STATES PATENT OFFICE.

HERMAN MOON AND JAMES M. REYNOLDS, OF GROVE CITY, PENNSYLVANIA.

FRICITION REVERSING MECHANISM.

1,072,145.

Specification of Letters Patent.

Patented Sept. 2, 1913.

Application filed November 1, 1912. Serial No. 729,103.

To all whom it may concern:

Be it known that we, HERMAN MOON and JAMES M. REYNOLDS, citizens of the United States, residing at Grove City, in the county 5 of Mercer, State of Pennsylvania, have invented a new and useful Friction Reversing Mechanism, of which the following is a specification.

The present invention relates to improvements in friction reversing mechanisms, the 10 primary object of the invention being the provision of a mechanism to be used in connection with gas or steam engines, and especially adapted when the gas or steam engine 15 is connected to operate drills for oil and water wells, the same being so constructed as to provide the necessary slow and steady movement during the drilling operation and to rapidly return the same after such operation.

20 A further object of the present invention is the provision of a novel form of friction reversing mechanism in which the motor power is connected directly for forward operation, the present mechanism being so connected as to readily transmit a reverse rotation 25 from the motor power to the desired mechanism to be operated.

With the foregoing and other objects in 30 view which will appear as the description proceeds, the invention resides in the combination and arrangement of parts and in the details of construction hereinafter described and claimed, it being understood that 35 changes in the precise embodiment of the invention herein disclosed can be made within the scope of what is claimed without departing from the spirit of the invention.

In the drawings—Figure 1 is a top plan 40 view of the mechanism as applied to the crank shaft of an engine. Fig. 2 is a section taken on line 2—2 of Fig. 1. Fig. 3 is an end elevation of the reversing mechanism. Fig. 4 is a section taken on line 4—4 45 of Fig. 1. Fig. 5 is an end elevation taken from the left as viewed in Fig. 1 of the complete mechanism.

Referring to the drawings, the numeral 1 50 designates the crank shaft of an explosive or steam engine carrying the balance or fly wheel 2, said shaft being extended beyond the fly wheel and having keyed upon the outer end thereof, the forward drive pulley 3, which is indicative of any form of power 55 transmitting means. Mounted upon the extended end of the shaft 1 between the pulley

3 and the fly wheel 2, is a sleeve 4 which carries the large friction disk 5 which is keyed or fastened to the fly wheel 2 by means of the bolt 6 and is provided with the angularly disposed friction surface 7. The reversing pulley or other power transmitting means 8 is rotatably mounted upon the extreme outer end of the sleeve 4, as clearly shown in Fig. 2, and has fastened thereto, 60 by means of the bolts 9, the large friction wheel or disk 10, which is oppositely disposed to the friction disk or wheel 5 and of the same diameter and is provided with the inclined friction surface 11 which corresponds with the friction surface 7 of the disk 5. It will thus be seen that when the shaft 1 is rotating, that the sleeve 4 will be rotated as will also the pulley 3, but as the pulley 8 and friction disk 10 is free to rotate 65 upon the sleeve 3, the same will not transmit motion while the power is being transmitted from the pulley 3 to the drilling mechanism or in fact any other mechanism that it is desired to operate.

In order to provide a means for properly transmitting reverse rotation to the pulley 8, a base 12 is provided and carries the two upstanding standards or posts 13—13', which constitute bearings for the respective 80 shafts 15 and 14, said shafts being connected together at their inner ends by means of the U-shaped frame 16, which is properly supported against downward movement by means of the post 17 carried by the base 12 85 and the plate 18 carried at the upper end of the post 17. Mounted upon the respective shafts 15 and 14 and freely rotatable are the frusto-conical friction rollers 19—19', which are disposed between the respective 90 beveled surfaces 7 and 11 of the friction disks 5 and 10, and under normal conditions are out of contact therewith so that no power is transmitted from the disk 5 to the disk 11, it being necessary to actuate these 95 disks through the shafts 14 and 15 so as to force the same frictionally between the respective inclined surfaces 7 and 11 so that power is transmitted from the fly wheel 2 and through the friction cones 19 and 19' 100 to the friction disk 11, said friction disk 11 being rotated in an opposite direction to the friction disk 5 so as to operate its pulley 8 in the opposite direction to the pulley 3, and thus transmit power in a reverse direction 105 to the mechanism to be affected. In order to accomplish this, a resilient sup-

port 20 is connected to the base 12 and carries at its upper free end, a sleeve 21, which has a plane face adjacent to the cone 19', while upon its opposite face is provided the 5 cam or inclined edge 22 with the abrupt shouldered portion 23, its sleeve 24 being held against rotation by the resilient rod 20 and also permitted a slight movement longitudinally of the shaft 14 to affect the forcing 10 of the cone 19' between the respective inclined surfaces of the friction disks 5 and 10. The operating lever which consists of the two spaced arms 24 have their apertures 25 rotatably mounted upon the shaft 14 and 15 straddle the upper end of the standard 13', said lever being operated to properly oscillate the respective sleeves 26 and 27, the outer faces of which are provided with corresponding cammed portions to engage the 20 sleeve 21 to force the same to move the cone 19' into frictional engagement with the disks 5 and 10, and to force the cammed sleeve 28 which is keyed upon the shaft 14 by means of the screw 29 outwardly, thus 25 imparting longitudinal movement to the shaft 14, frame 16 and the shaft 15 so as to pull the cone 19 in an opposite direction to the cone 19' and into frictional engagement between the disks 5 and 10 at a diametrically 30 opposite point from the engagement of the cone 19' therewith.

When the friction mechanism is out of operation and the pulley 3 is being operated directly, the lever 24 is in the position as 35 shown in Fig. 5, and when it is desired to reverse the rotation of the belt (which is not shown), the lever 24 is moved to the dotted line position Fig. 5, actuating the shafts 14 and 15 as indicated to move the cone 19 into frictional engagement with the disks 5 and 10 and simultaneously actuating the sleeve 21 to throw the cone 19' into such engagement, thus transmitting the desired reverse rotation to the pulley 8. Where a 40 belt is used, it is desirable that the belt be shifted simultaneously with the movement of the lever 24 from the full to the dotted line position and vice versa, and in order to accomplish this, the belt engaging arm or 45 shifter 30 is carried by the lever 24. The sleeve 31 is secured upon the shaft 15, and as the shaft is moved longitudinally through the cam sleeves 27 and 28, this sleeve 31 abuts and forces the cone 19 into frictional 50 engagement with the disks 5 and 10, and simultaneously with the movement of the cone 19' into such engagement.

What is claimed is:

1. The combination with a driving shaft, 60 and a power transmission means on the free end thereof, of a friction reversing mechanism including a sleeve fast to the shaft, a friction disk carried by said sleeve, a reverse transmission means rotatably mounted upon the sleeve, a friction disk carried by

said last transmission means and opposed to the first mentioned friction disk, two oppositely disposed friction cones disposed between the friction disk, and means for moving the cones toward each other and into 70 frictional engagement with the friction disks to transmit reverse rotation from one disk to the other.

2. The combination with a driving shaft, 75 and a power transmission means on the free end thereof, of a friction reversing mechanism including a sleeve fast to the shaft, a friction disk carried by said sleeve, a reverse transmission means rotatably mounted upon the sleeve, a friction disk carried by 80 said last mentioned means and opposed to the first mentioned friction disk, two oppositely disposed friction cones disposed between the friction disks, two longitudinally 85 slidable shafts connected for movement in unison and disposed transversely of and between the friction disks, two friction cones, one to each slidable shaft, rotatably and slidably mounted upon said slidable shafts and 90 between the friction disks, and means for sliding the two shafts to effect the movement of the friction cones into engagement with the friction disks.

3. The combination with a driving shaft, 95 and a power transmission means on the free end thereof, of a friction reversing mechanism including a sleeve fast to the shaft, a friction disk carried by said sleeve, a reverse transmission means rotatably mounted upon the sleeve, a friction disk carried by 100 said last transmission means and opposed to the first mentioned friction disk, two oppositely disposed friction cones disposed between the friction disks, two longitudinally 105 slidable shafts connected for simultaneous sliding movement and mounted transversely of and between the friction disks, two friction cones, one to each slidable shaft, mounted upon said slidable shafts and 110 opposed at diametrically opposite points to the friction disks, two cone engaging means mounted upon the two slidable shafts for moving respective cones toward each other and into frictional engagement with the friction disks, and manually operated 115 means for sliding the two shafts to operate one of said cone engaging means and for sliding the other of said cone engaging means to move the cones toward each other and into frictional engagement with the 120 disks.

4. The combination with a driving shaft, 125 and a power transmission means on the free end thereof, of a friction reversing mechanism including a sleeve fast to the shaft, a friction disk carried by said sleeve, a reverse transmission means rotatably mounted upon the sleeve, a friction disk carried by 130 said last transmission means and opposed to the first mentioned friction disk, two oppo-

sitely disposed friction cones disposed between the friction disks, a supporting frame mounted transversely of and upon opposite sides of the friction disks, two shafts 5 journaled in said frame for sliding movement and connected for movement in unison, a friction cone mounted slidably and rotatably upon the respective shafts and disposed for engagement with the friction disks 10 at diametrically opposite points, a cam sleeve slidably mounted upon one of the shafts and disposed for operating the cone mounted upon the same shaft, another cam sleeve keyed upon the same shaft and in spaced relation to the first cam sleeve, and 15 two manually operated oppositely disposed

cam sleeves mounted upon the shafts between the two first mentioned cam sleeves whereby the movement thereof will slide one cone into engagement with the friction disks and slide the shafts to move the other cone simultaneously in engagement with the friction disks. 20

In testimony that we claim the foregoing as our own, we have hereto affixed our signatures in the presence of two witnesses. 25
